STORAGE BATTERY

Roger A. Worrell, Fullerton, Calif., assignor to The Electric Storage Battery Company, a corporation of New Jersey

Filed May 25, 1962, Ser. No. 70,289

Term of patent 14 years

(Cl. D26—6)

FIG. 1

FIG. 2

FIG. 3

FIG. 4

FIG. 5

FIGURE 1 is a perspective view of a storage battery, showing my new design;

FIG. 2 is a front elevational view;

FIG. 3 is an end elevational view;

FIG. 4 is a top plan view;

FIG. 5 is a bottom plan view; and

FIG. 6 is an enlarged sectional view of a portion of an end showing the surface of the end and taken along line 6—6 in FIG. 3.

The rear and end of this storage battery not shown are identical to the front and end shown.

The design for the disclosed storage battery is characterized by having an inwardly stepped bottom portion on all sides of the battery and having identical indented labeling panels on both ends of the battery, said labeling

panels extending from a projected top portion of the battery to the stepped bottom portion and being bounded on both side edges by substantially parallel vertical beads which also extend from the projected top portion to the stepped bottom portion of the battery.

I claim:

The ornamental design for a storage battery, as shown and described.
